Primary Examiner — Khawaja Anwar*Assistant Examiner* — Taylor O Mortorff(74) *Attorney, Agent, or Firm* — Daniel M. Cohn;
 Howard M. Cohn(57) **CLAIM**

The ornamental design for an air duster as shown and described.

DESCRIPTION

FIG. 1 is a perspective view of an air duster showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines in the drawings depict portions of the air duster that form no part of the claimed design.
